IRONING BOARD AND CABINET THEREFOR

Alpha Perry Lantz, Washington, D. C.

Application May 14, 1946, Serial No. 669,661

3 Claims. (Cl. 38—129)

1

This invention relates to improvements in ironing boards and cabinets therefor and has for its object the provision of a cabinet either as a part of a permanent building structure, or as a separately formed unit to be attached to a wall of a room or the like, combined with means for supporting and bracing a pair of ironing boards (one the customary board of normal size and the other a relatively smaller sleeve board) in a novel manner affording great strength in their ironing operations, and requiring a minimum amount of space in their stored or inoperative positions within the cabinet.

The preferred embodiment of the invention comprises the cabinet and the pair of normal and sleeve boards pivoted in the cabinet, in close vertical parallel planes whereby the boards when stored or closed in the cabinet will overlap and reduce the space required to accommodate the length of the boards, and permitting the boards to be swung outwardly from the cabinet into horizontal planes approximating that customarily desired above the level of the floor, to accommodate the user and avoid awkwardness or inconvenience of the user that would otherwise result from the respective ironing positions of the board being at abnormal or greatly varying ironing positions.

To these ends the ironing boards and cabinet are conjointly provided with combined side wall tying rods or braces and pivoting members, together with abutting portions between the inner ends of the boards and recessed portions in the back wall of the cabinet whereby the boards will be swingingly mounted in the cabinet and the boards in ironing position will be firmly reinforced, in ironing position, by the bodies of the side and rear walls of the cabinet as distinguished from supplemental stops or braces customarily added to said walls as separately formed or added attachments.

Ancillary features of the improvements comprise improved means for automatically opening the boards to ironing position, or for closing the same to nested or closed position in the cabinet, combined with means for latching the same against said automatic operation.

Other novel and improved details, such as the special formation of the back wall of the cabinet with recessed or cut away portions inwardly of

2

the face thereof to constitute the aforesaid inner end abutments for the boards; combined braces and pivot portions for the boards; fasteners for a protecting cover or padding instrumentalities for the boards; and iron supporting means to retain the iron when at rest, against falling from the board, especially in the instance of the relatively narrow sleeve board.

All of the foregoing, together with various details or refinements, will be fully understood from the detail description hereinafter contained when read in connection with the accompanying drawings forming a part hereof, and wherein said preferred embodiment of the invention is illustrated.

In the drawings:

Figure 1 is a front elevation of the structure, parts being broken away, the door of the cabinet being open with the ironing boards in projected or ironing position, the boards being shown in cross-section.

Figure 2 is a similar view with the boards in closed or nested position in the cabinet.

Figure 3 is a vertical sectional view taken on the line X—X of Figure 1, looking to the right.

Figure 4 is a similar view taken on the line Y—Y of Figure 2.

Figure 5 is a top plan view of the inner end of the sleeve board, particularly illustrating the iron holder attached thereto and immediately associated parts.

Figure 6 is a top plan view of the rear end of the other board showing its iron holder, and reinforcement and attaching means for a cover or pad.

Figure 7 is a detail vertical sectional view (on the line Z—Z of Figure 4) through the back wall of the cabinet showing the latching means for the main board.

Figures 8 and 9 are respectively a plan view and vertical section of another form of latching means for the main board.

Referring more particularly to the drawings, wherein like reference numerals designate the same parts in the several views, the cabinet for the ironing boards is shown as rectangular in cross-section, comprising an upright rear wall 10, side walls 11 extending forwardly therefrom and a hinged door or closure 12, portions of this structure being broken away to enable a better illustration of the contents of the cabinet.

Bridging the space within the cabinet are a pair of shafts 13 and 14, these shafts performing the double function of bracing the side walls and as pivotal mountings respectively, for the main ironing board 15 and the sleeve board 16.

The boards differ in their construction primarily in the length and width thereof, the sleeve board, of course, being considerably smaller in these respects, throughout, as compared to the main board.

The shafts 13 and 14 are arranged one above the other (Figure 3) and in spaced vertical planes. The shaft 14 of the sleeve board is relatively adjacent to the back wall 10 of the cabinet and the shaft 13 of the main board relatively adjacent to the front portion of the cabinet in order that the boards 15 and 16, when closed or stored in the cabinet, may occupy parallel positions vertically within the cabinet, and also, when the boards are in their horizontal or outward projecting and operating positions may occupy planes conveniently and comfortably accessible to the user.

Underneath the inner end of the main board 15, and secured thereto by rivets 17, is an inverted Y-shaped brace having side portions 18 extending along the edges of the board, a connecting intermediate portion 19 extending transversely across the board and a longitudinal brace 20 extending outwardly centrally of the board, to strengthen the latter and to brace and secure opposite loop portions 21 formed to accommodate the shaft 13.

Near the opposite ends of the shaft 13, and between the edges of the board 15 and the inner faces of the side walls 11, are coiled springs 22 sleeved upon the shaft 13, each spring having one offset end 23 engaged with the adjoining side wall 11, and an opposite end portion 24 engaged with the edge of the board 19, the spring being of a character either to throw the board vertically in stored position or outwardly to ironing position, the function in the present instance being the former, that is, to throw the board upwardly to vertical or stored position in the cabinet. In such case means must be afforded to overcome the closing or storing tendency of the springs by latching the board against closing movement when the same has been swung outwardly into ironing position, such means comprising a hook 25 pivoted to the back wall 10 of the cabinet, having a handle 26 and an offset end 27 to engage a complementary loop 28 struck out from or formed on the plate 29 fastened to the upper surface of the board 17 by rivets or bolts 30 passing through the same and through the underlying plate 19. The plate 29 is intended, not only to reinforce the inner portion of the board 15, but is also shaped with an upstanding rib 32 marking the margin of a slightly raised platform or rest 33 to support and prevent slippage of an iron from the board.

The outer edges of the plates 19 and 29 are formed with a series of hooks 34 and 35 adjacent to the under and upper surfaces, respectively, of the board 15 to afford a means of attachment for any suitable covering or padding, if desired, placed on the operating face, or sleeves over the end of the board, the latter being conveniently indicated in Figure 2 as having rods 36 embedded in its opposite ends with separated exposed portions 37, afforded by complementary cut-away portions of the covering as at 38, to expose parts of the rod for slipping over and engaging with the adjacent hooks.

A very important feature of the present invention resides in the means for bracing or reinforcing the board, in its ironing position, from the

entire rear wall 10 of the cabinet for forming said rear wall with integral abutting portions for the inner ends of the boards to bear the ironing pressures on that portion of said boards that project outwardly beyond the pivots thereof. This obviates the complications and expense attending the provision of special brackets, stops, or abutments separately formed and attached to the surface of the wall, as by nails, screws or the like, as well as providing a structure wherein the inconvenience or trouble of said separate device, and their fastening means, becoming loose or disarranged is avoided.

To these ends the rear wall 10 has formed in its inner face channel portions 39 and 40, respectively, the former for the lower or main board 15 and the latter for the upper board 16. These channel portions constitute vertically disposed ways 41 and 42 in which the inner ends 43 and 44 of the boards 15 and 16 will enter when the boards are in operating position so that the flat upper surfaces of the boards will contact and abut the horizontal or flat tops 45 and 46 constituting the upper end walls of the channels, the inner walls of the latter being in part vertical and in part curved downwardly and forwardly as at 47 and 48, in the arc of movement of the boards on their pivots 13 and 14, the extreme inner ends of the boards themselves being rounded to prevent any possibility of interference with the swinging of the inner ends of the boards into or out of said ways.

At the opposite ends 49 of the channel portion 39 (and obviously the same may be utilized in connection with the channel portion 40) a pair of spring snap fasteners 50 are secured, as at 51, intervening reinforcing plates 52 being provided for the secured ends of said springs and the elongated free portions of the spring carrying seats or sockets 53 into which the ball-like heads 54 of pins fastened in the adjacent edges of the board 15, will snap as they ride up the springs 50 in the opening movement of the board. This affords a practical and efficient latch for the board, in its extended position, and for usual purposes will be sufficient where the thrusting spring 22 of the board acts to throw the board outwardly, but in embodiments where the spring action is reverse, namely to throw the board inwardly into the cabinet, the supplemental fastener constituted by the hook 28 and loop 27 heretofore referred to will also be employed.

The springs for throwing the sleeve board into operative or ironing position are indicated at 55, the same being anchored at one end 56 to the rear wall 10 of the cabinet and at its opposite end 57 to the side of the sleeve board 16, the coil of the spring having a constant urge in the direction of opening movement of the sleeve board, and the top wall 46 of the channel portion 40 of the back being lined with a rubber or shock absorbing material 58 so that when the board is released and thrown outwardly from the cabinet and the inner end of the board abuts said shock absorbing material the operation will be noiseless.

When the sleeve board 16 is forced into closed or rested position in the cabinet against the opening pressure of the springs 55, the sleeve board may be retained in its said closed position by a hook-latch 59 pivoted on the rear wall 10 at 60, and formed with a handle 61 and offset end 62 movable in a plane parallel to the rear wall to pass and hook over the under face of the sleeve board 16, when closed to parallel position with

the rear and thereby latch the sleeve board to hold the same against opening movement thereof until the hook 62 has been swung through manipulation of the handle 61, to pass out of the range of movement of the sleeve board and thereby free the same for outward swinging movement.

The edges of the channel portions 39 and 40 may be reinforced by a metal plate 63, or similar angular corner plate 64, as desired, to correspondingly reinforce or protect the corner edges of the rear wall 10, it being appreciated that said wall and cabinet may be formed of wood, or plastic material, wherein reinforcements of the shoulder or bearing portions at the upper ends of the channel portions may be expedient or desirable.

At the inner end portion of the sleeve board 16 an iron rest 65, secured to the face of the board, similar to the securing of the iron rest 33 to the board 15, this rest 65 having upstanding ribs or retaining flanges 66 and 67 to prevent displacement of an iron placed thereon. The iron rests 33 and 65 are of metal formation, as shown in Figure 3, elevated slightly above the surface of the boards to which the same are attached, to provide an air space therebetween.

The channel portions 39 and 40 are of a width approximately the width of the board that engages therein so that the end of the board will be substantially confined between end walls of the ways with reference to the side edges of the boards, so that there may be no substantial lateral play or movement of the boards from normal position.

In the embodiment of the invention utilizing an outwardly thrusting spring, as in the case of the sleeve board (Figure 3), in lieu of an inwardly closing spring, as in the case of the main board, (same figure), it would, of course, be desirable in instances to have an automatically acting lock to retain the board from being thrown to open position forwardly of the cabinet. To supply such a need the invention embraces the form of an automatic latch illustrated in detail in Figures 8 and 9. This latch comprises a supporting bracket 68, attached to the forward corner edge of one of the side walls 11 of the cabinet and bearing twin cylindrical casings 69 projected inwardly within the cabinet said cylindrical portions 69 containing outwardly thrusting coiled springs 70 abutting a vertical pin 71, working in slots 72 of the cylindrical portions and carrying at the ends of said pin 71 a sliding and rocking hollow keeper or bolt 73, adapted to spring in front of the board 16, or 15, as the case may be, when closed into the cabinet. The hollow bolt or keeper 73 pivots on the pin 71 so that in the closing of the board into the cabinet the board will strike the outer edge of the bolt and rock the same inwardly from the extended position (Figure 8) when the board may pass inwardly therebeyond, after which a spring 74, also sleeved on the pin 71 and bearing at one end on the inner face of the forward wall of the bolt 73, and the corresponding face of the connecting plate 75, between the cylindrical portions 69, will rock the bolt back to normal aligned position with the cylindrical portions 69 and firmly hold the board against movement out of the cabinet. It will be appreciated that the bolt 73 will not only rock on its pivot 71 but may also move inwardly with said pin as allowed by the slots 72.

To retract the bolt against the pressure of the springs 70, so that the ironing board will be re-

leased from behind the bolt and may be thrown or moved forwardly to ironing position, a handle 76 is provided, the same being pivoted to the bolt 73, and normally it may occupy a position along side the bolt, that is, parallel thereto, so as to offer no projection to interfere with the closing of the door 12 of the cabinet; and when the bolt is to be withdrawn to permit opening of the board the said handle 76 may be swung outwardly and grasped in pulling the bolt back over the cylindrical portions 69 and connecting web 75.

It will be understood that the invention may be incorporated with other devices or embodied in forms and arrangements differing in detail from the illustrations herein, without departing from the spirit of the invention and in keeping with the hereto appended claims.

I claim:

1. The combination with an ironing board, of means for supporting the same when in opened or closed position, said means comprising a cabinet having a rear and side walls, means bridging said side walls and constituting a pivotal support therebetween with which the board is operatively connected to be moved into or out of the cabinet, means for thrusting the board to one of its positions, and means in rear of said pivotal support and formed integral with and within said rear wall to engage an entering part of the ironing board and brace the same when in outward or ironing position, and a spring latch located in the rear wall adjacent to the entering part of the board and adapted to be engaged therewith when the board is in ironing position.

2. The combination with an ironing board, of means for supporting the same when in opened or closed position, said means comprising a cabinet having a rear and side walls, means bridging said side walls and constituting a pivotal support therebetween with which the board is operatively connected to be moved into or out of the cabinet, means in rear of said pivotal support to engage a part of the ironing board and brace the same when in outward or ironing position, the pivotal supporting means for the board comprising a cross-rod connected to the side walls of the cabinet and bearing portions on the board sleeved on said rod, said bearing portions including a plate underlying the board with the bearing portions formed therein, a companion plate overlying the board, means passing through the board fastening the plates together to reinforce the bearing portions, and hooks formed on the outer edges of the plates and carried thereby for attachment of a cover or pad.

3. The combination with an ironing board, of means for supporting the same when in open or closed position, said means comprising a cabinet having a rear and side walls, said rear wall being provided with a recess bound by a top and side walls, a rod bridging the side walls of the cabinet and constituting a pivotal support therebetween with which the board is operatively connected to be moved into and out of the cabinet, said top and side walls of the recess providing means to the rear of the pivotal support to engage an entering part of the ironing board to brace the same when in ironing position, the side walls of the recess being spaced apart a distance approximately equal to the width of the entering part of the ironing board to prevent lateral movement thereof, and spring latches mounted on said side walls of the recess adjacent

to the entering part of the board and adapted to be engaged therewith when the board is in ironing position.
